UNITED STATES PATENT OFFICE.

LINA PRAGER WEBER, OF NEW YORK, N. Y.

DESIGN FOR A GOFFERING-TOOL.

SPECIFICATION forming part of Design No. 32,332, dated March 13, 1900.

Application filed February 7, 1900. Serial No. 4,405. Term of patent 14 years.

To all whom it may concern:

Be it known that I, LINA PRAGER WEBER, a citizen of the United States, residing at the city of New York, borough of Manhattan, county and State of New York, (whose post-office address is 96 Bleeker street, in said city,) have invented and produced a new and original Design for a Goffering-Tool, of which the following is a specification.

10 My invention relates to the design for a tool used in manufacturing artificial flowers; and the essential feature of the same is the configuration of the tool, as herein shown and described.

15 In the drawings forming part of this specification, Figure 1 is a plan view; Fig. 2, an end elevation; Fig. 3, a side elevation, and Fig. 4 an inverted plan view.

The body 1 is circular and non-continuous 20 and in cross-section, as seen from the end view, Fig. 2, is wedge-shaped, the outer sur-

face 2 being on a less-acute angle than the inner surface 3. At the apex of the wedge or meeting points of the surface 2 3 is formed a head 4, which is flush with the surface 3 and extends beyond the surface 2, as shown in Fig. 2, and which partakes of the disposition or curvature of the body 1. Centrally from the plan top 5 of the body 1 is a circular rod 6.

The sides 7 of the body 1 are slightly inclined. (See Fig. 3.)

Having described my invention, I claim—
The design for a goffering-tool, substantially as herein shown and described.

Signed in the city, county, and State of New York this 5th day of February, 1900.

LINA PRAGER WEBER.
